UNITED STATES PATENT OFFICE.

WILLIAM S. BING, OF SAN DIEGO, CALIFORNIA.

HAND-STAMP.

1,048,281.

Specification of Letters Patent. Patented Dec. 24, 1912.

Application filed July 12, 1911. Serial No. 638,091.

To all whom it may concern:

Be it known that I, WILLIAM S. BING, a citizen of the United States, and a resident of San Diego, in the county of San Diego and State of California, have invented certain new and useful Improvements in Hand-Stamps, of which the following is a specification.

My invention relates to hand stamps which are used in connection with an ink pad for the purpose of stamping designs on objects.

The objects of my invention are to provide a device of this character that is simple and economical of construction, and that may be used for stamping designs on convex as well as flat surfaces.

With these and other objects in view as will appear, my invention consists of certain novel features of construction, combination and arrangement of parts, as will be herein-after described in detail and particularly set forth in the appended claim, reference being had to the accompanying drawings and to the characters of reference thereon, which form a part of this specification, in which:—

Figure 1 is a top view of my hand stamp, Fig. 2 is a sectional view shown in position for inking the stamp and for stamping flat surfaces, and Fig. 3 is a sectional view showing its position when used for stamping objects with convex surfaces.

Similar characters of reference refer to similar parts throughout the several views. The handle 1, plunger 2, elastic pad 3, spring ring 4, and design pad 5, constitute the parts of my hand stamp.

The handle 1 is preferably shaped as shown best in Figs. 2 and 3, the upper portion being adapted for the hand and provided with a flat surface on its top. The lower end is enlarged and provided with a tapered recess 1^a, which extends up into said handle some distance. From this recess to the top is provided a hole adapted for the plunger 2. This plunger is provided on its lower end with a head 2^a and the plunger is the same length as the handle, so that when it is flush at the top the lower end is flush with the lower edge of the handle. The

lower outer surface of the handle is cut away and is provided with a groove adapted for the ring 4. Said ring 4 is a spring ring adapted to spread sufficiently to pass over the portion 1^b and rest in the groove. Over 55 this lower end is placed an elastic pad 3, and the ring is pressed over the same into the groove. This provides a substantial fastening for the elastic pad, stretching the same to give it a proper surface. 60

Centrally located on the lower surface of elastic pad 3 is design pad 5 of approximately the same diameter as the plunger head 2^a. When using the hand stamp, the plunger 2 is pressed down flush as shown in 65 Fig. 2, then it is inked in the usual manner by applying thereto an ordinary inking pad, and if it is desired to stamp a flat surface, the pressure on the plunger is continued on the end of plunger 2, and the stamping is 70 made in the usual manner.

In case it is desired to stamp an object with a convex surface, the plunger 2 is released after inking and the elastic pad 3 and the design pad 5 conforms readily to the 75 convex surface as shown in Fig. 3.

It is obvious that with this construction, there is provided a simple and economically constructed hand stamp, and that it may be used for both flat and convex surfaces. 80

Though I have shown and described a particular construction, I do not wish to be limited to this particular construction, but desire to include in my invention the construction substantially as set forth in the appended 85 claim.

Having thus described my invention, what I claim as new and desire to secure by Letters Patent is:—

A hand stamp comprising a torose shaped 90 hand piece, provided with a hole extending longitudinally through the center thereof, connecting with a cap-shaped chamber in the lower end thereof, an elastic pad stretched over the lower end of said chamber 95 and extending up over the lower end of said hand piece, a plunger, a portion of which is adapted to reciprocate in said hole provided with an enlarged circular shaped lower end, the lower surface of which is flat adapted to 100

press against said elastic pad and place it into position for inking said stamp, a design pad mounted centrally on said elastic pad over said chamber, a spring ring means 5 for facilitating the stretching of said elastic pad over said hand piece and for attaching it to the same, all substantially as set forth.

In testimony whereof, I have hereunto subscribed my name in the presence of two subscribing witnesses.

WILLLIAM S. BING.
